FIRE HOSE CABINET

Chauncey A. Cornell, Detroit, Mich.; Aileen F. Cornell, administratrix of Chauncey A. Cornell, deceased

Application August 9, 1937, Serial No. 158,177

3 Claims. (Cl. 299—80)

The invention relates to fire apparatus of the type permanently installed in buildings and comprising a hydrant and a hose attached thereto and stored in an adjacent cabinet. With such apparatus the water is usually supplied under high pressure so that before the valve can be safely opened it is essential that the hose should be straightened. This usually requires the service of two men; one to draw out the hose and straighten the same; and the other to open the valve. It is the object of the present invention to obtain a construction which may be safely operated by one man and in which the water will be automatically turned on as soon as the hose is in condition to receive the same. It is a further object to obtain an improved form of cabinet in which the hose is stored and which facilitates the very rapid withdrawal of the same. With these and other objects in view, the invention consists 20 in the construction as hereinafter set forth.

In the drawings:

Figure 1 is a front elevation of the cabinet with the door open, but showing the mechanism within the casing in the position where the door 25 is closed;

Figure 2 is a horizontal section on line 2—2 of Figure 1;

Figure 3 is an enlarged horizontal section through the hose supporting rack;

Figure 4 is a cross section thereof on line 4—4 of Figure 3;

Figure 5 is a perspective view of the open cabinet with the mechanism in position where the door is open;

Figure 6 is a vertical section through the valve;

Figure 7 is a sectional side elevation of the valve and its operating mechanism.

My improved apparatus comprises a cabinet A provided with a hinged door B, preferably having a glass panel C through which the contained apparatus may be seen. Leading into this cabinet is a water conduit D attached to a fitting E, which latter contains a quick opening valve F and a hose connection G. It may also, if desired, be provided with a manually operable valve H controlling a separate hose connection I. J is a hose connected to the fitting G and normally stored within the cabinet at one side thereof.

One of the features of my improvement is the 50 means for holding the hose in stored position which as soon as the cabinet door is opened, will automatically move it into a position for quick withdrawal. This means comprises a bracket arm K which is pivotally attached to a bracket K' near the upper end and center of the cabinet so that

when the arm K is turned inward, it will extend from the center to one side. Pivotally attached to the free end of the arm K is a hose rack L which normally lies adjacent to the side of the cabinet extending from the rear to the front thereof and being adapted to support a series of hose loops. In specific construction this rack comprises an inverted channel-shaped member L' of a width to receive the folded hose loops, rods L² and L³ extending adjacent to the opposite sides of this channel within the same, and a series of transversely extending supporting bars L⁴. Each of the bars L⁴ is formed with an eye L⁵ at one end thereof which slidably engages the rod L³. At the opposite end the bar L⁴ has a portion L⁶ which rests upon the rod L², the latter, as shown, being formed by a slotted return-bent flange on one side of the member L'. The rod L³ with which the eyes L⁵ are engaged, extends outward through the forward open end of the channel L' and is then curved to form a segmental loop L⁷. The other rod L² ends within the channel and the arrangement is such that each of the cross rods L⁴ when drawn outward on the rods L² and L³ will first disengage the end L⁶ to allow it to drop and will then be swung around the loop L⁷. This permits of successively drawing out the loops of the hose and as each bar L⁴ is disengaged from the rod L² it will free the loop and will itself be moved out of the path of a succeeding bar.

The valve F which controls the passage of water from the conduit D to the hose fitting G is adapted to be quickly opened after the hose is withdrawn from the rack. To accomplish this the valve preferably comprises a disk F' which is closed against the seat F² against the water pressure being provided with a guide stem F³ and an operating stem F⁴. The latter extends upward through the cover F⁵ and is threaded at its upper end to receive the adjustable bearing F⁶ and locknut F⁷. The bearing F⁶ engages a cam M on a shaft M' journaled in brackets M² rising from the cover F⁵. M³ is a lever attached to the shaft M' normally extending upward therefrom and engaging a bifurcated bracket M⁴ in which position the cam M engaging the stem F⁴ will hold the valve F' to its seat. The outer end of the lever M³ is connected by a strap M⁵ with a loop J' in the hose J extending upward from the 50 hose fitting G. Thus, whenever the hose is drawn out and straightened this loop J' through the strap M⁵ will pull downward the lever M³, turning the cam M to a position where the valve disk F' will be automatically opened by the water 55

pressure. Accidental operation of the lever is prevented by spring clips M^6 in the bifurcated bracket M^4 , the tension of which is sufficient to normally hold the lever from disengagement.

- 5 When the hose J is drawn out from the cabinet it may be carried in any direction therefrom before it is completely straightened. I, therefore, provide means for automatically swinging the arm K outward whenever the cabinet door B is opened and into a position where its outer end is at the center and completely clear of the cabinet. This permits the rack L to turn on its pivotal connection with the arm K into alignment with the direction in which the hose is being drawn, thereby permitting the loops to be easily disengaged from the channel L' and the bars L^4 . The means for actuating the arm K is a spring K^2 secured to the cabinet and bearing against said arm when in folded position and the door 10 of the cabinet bearing against the outer end of the channel member L' will hold the parts in this position as long as the cabinet is closed, but as soon as the door is opened the spring will throw the arm K outward into the central position. To hold it in this position there is a bracket N secured to the top of the cabinet having a finger N' forming a stop for the arm K on one side and a latch finger N^2 for engaging the opposite side of the arm. The outer end of the hose is provided with a suitable nozzle O which has a flange 15 O' for supporting it in a slotted bearing at the outer end of the channel L' .

With an apparatus constructed as above described, whenever it is needed for use it is only necessary for the operator to open the cabinet door take hold of the nozzle O and draw the hose outward in the direction in which it is needed. After all of the loops supported on the bars L^4 have been disengaged therefrom, the final 20 straightening of the hose will draw downward the loop J' , and this actuating the lever M^3 and the cam M will permit the automatic opening of the valve F' by water pressure. The fact that the hose has been drawn straight before the 25 water is released will prevent any reaction which would otherwise occur. To avoid any danger of the valve sticking to its seat a lever M^7 engaging a fulcrum M^8 has one end extending beneath the nut F^7 and the other end in the path of the lever 30 M^3 . Thus the pulling down of the lever by the hose will positively disengage the valve from its seat.

If desired, the cabinet may also be provided with an electric light P controlled by a switch Q 35 which will be automatically closed when the door

B is opened, thereby providing the necessary illumination. The strap M^5 is in the form of a loop of sufficient size not to restrict the hose when filled out by water pressure.

What I claim as my invention is:

1. In a fire apparatus, a cabinet, a hydrant within said cabinet, an arm pivotally secured within said cabinet to swing outward therefrom, a hose support pivotally secured to the free end of said arm, said support including a series of 10 arms for engaging individual hose loops, guides on which the opposite ends of said arms are slidably supported, said arms being permanently secured to one of said guides and slideable off the end of the other guide, whereby drawing the 15 end of said hose will swing said arm out of said cabinet carrying the hose support therewith and the individual loops of said hose will be successively disengaged from said arms.

2. In a fire apparatus, a cabinet having a door 20 for closing the same, a hydrant within said cabinet, an arm pivotally secured within said cabinet, a hose support pivotally secured to the free end of said arm, said support including a series of 25 arms for engaging individual hose loops, guides on which the opposite ends of said arms are slidably supported, said arms being permanently secured to one of said guides and slideable off the end of the other guide, and means automatically operating upon the opening of the door of said 30 cabinet for swinging said first mentioned arm and the hose support pivotally secured thereto out of said cabinet, whereby the drawing of said hose will successively disengage said loops from 35 their supporting arms.

3. In a fire apparatus, a cabinet, a door for closing said cabinet, a hydrant within said cabinet, an arm pivotally secured within said cabinet to swing outward therefrom, a hose support pivotally secured to the free end of said arm, 40 said support including a series of arms for engaging individual hose loops, guides on which the opposite ends of said arms are slidably supported, said arms being permanently secured to one of said guides and slideable off the end of the other 45 guide, means automatically operating upon the opening of said door for swinging said first mentioned arm with its free end out of said cabinet, and latch means for holding said arm stationary in its outer position, whereby the drawing of said 50 hose in any direction will permit the successive disengagement of said loops from the arms supporting the same.
